The ornamental design for cephalometry sheet set, as shown and described.

DESCRIPTION

FIG. 1 is a first sheet of a cephalometry sheet set shown separately for clarity of illustration showing our new design; and,

FIG. 2 is the second sheet of a cephalometry sheet set shown separately for clarity of illustration.

Portions of FIGS. 1-2 that are shown in dashed lines are for illustrative purposes only and form no part of the claimed design.

1 Claim, 2 Drawing SheetsFIG. 1

FIG. 2
